(57) **CLAIM**

The ornamental design for a medical instrument, as shown and described.

DESCRIPTION

1. Medical instrument

1.1 : Front

1.2 : Back

1.3 : Left

1.4 : Right

1.5 : Top

1.6 : Bottom

1.7 : Perspective

1.8 : Exploded

A medical instrument; representations show front, back, left, right, top, bottom, perspective and exploded views; features shown in dotted or dashed lines are disclaimed and do not form part of the design; contour lines show surface shapes.

1 Claim, 8 Drawing Sheets
